UNITED STATES PATENT OFFICE

WINFRED S. GRIFFITH, OF WORCESTER, MASSACHUSETTS, ASSIGNOR TO GRATON & KNIGHT COMPANY, OF WORCESTER, MASSACHUSETTS, A CORPORATION OF MASSACHUSETTS

MECHANISM AND METHOD FOR CEMENTING DOUBLE LEATHER BELTS

Application filed April 26, 1929. Serial No. 358,403.

This invention relates to the manufacture of leather belts in which two previously formed single belts are cemented together to form a belt of double thickness. In the manufacture of such belts, it is particularly essential that the edges of the single belt layers shall be firmly secured to each other, as any crack or opening along the edges of the double belt detracts seriously from its value.

It is the general object of my invention to provide a mechanism by which an increased pressure is applied to the edge portions of the double belt while the cement is setting, causing more firm adherence of the edge portions to each other.

A further object of the invention is to provide an improved method of cementing belts by which more acceptable results may be attained.

My invention further relates to arrangements and combinations of parts which will be hereinafter described and more particularly pointed out in the appended claims.

A preferred form of the invention is shown in the drawings in which

Fig. 1 is a side elevation, partly in section, of portions of a belt cementing machine adapted for the carrying out of my invention;

Fig. 2 is an enlarged plan view of certain parts shown in Fig. 1;

Fig. 3 is a detail sectional view of a portion of the roll of belt; and

Fig. 4 is a view similar to Fig. 3 but showing an additional use of the invention.

Referring to the drawings, I have shown upper and lower belt layers A and A' each preferably formed of single ply strips of leather having their overlapping skived ends cemented or glued together to form a continuous single belt. The belt layers A and A' are fed between drawing rolls 10 and presser rolls 12 and after passing through the machine, the double belt B is wound on a drum 15.

As the layers A and A' approach the drawing rolls 10, a layer of celluloid C is drawn through a bath 17 of a suitable solvent and is inserted between the layers A and A', thus

providing the necessary cementing material to secure the layers firmly together.

The drum 15 is preferably provided with wings or guide members 20, bolted in spaced relation on the periphery of the drum and also adjustable axially in accordance with the width of the belt to be wound on the drum. Suitable driving mechanism (not shown) is provided for frictionally rotating the drum 15, winding the belt thereon under relatively heavy tension exerted against the retarding action of the friction rolls 12.

A main object of my invention, as previously stated, is to relatively increase the pressure applied to the edge portions of the belt as it is wound on the drum 15. For this purpose I provide spools S (Fig. 2) rotatably mounted on a cross rod 25 and held in spaced relation by collars 26. Strips of tape T are drawn from the spools S and are guided around a cross bar 27 and under guide-rolls 28 mounted on a cross shaft 30. The guide-rolls 28 are grooved to receive the tapes T and are secured in spaced relation on the shaft 30 by set screws 32. The shaft 30 is freely rotatable by the friction of the tapes as they are drawn under the guide-rolls 28.

Having described the essential features of my invention, the method of operation and advantages thereof are as follows:

As the cemented belt B is drawn from the presser rolls 12 and is wound on the drum 15, the ends of the tapes T are inserted at the bite of the belt as it is wound on the roll and adjacent the extreme edge portions thereof.

As the winding of the belt continues, the tapes are fed accurately by the guide-rolls 28 to the edge portions of the belt B, so that the roll of belt is relatively thickened at the edge portions, as indicated on a somewhat exaggerated scale in Fig. 3. It is evident that the winding tension and pressure is exerted very largely at the extreme edge portions of the belt B, at the points where the tapes T are inserted, while the middle portions of the belt are under relatively light pressure.

The belt is allowed to remain on the drum 15 until the cement has fully set. The setting of the cement with the edges under excess

pressure practically eliminates the formation of cracks or openings along the edges of the completed belt, thus avoiding the production of seconds and substantially increasing the 5 value of the belt.

As the belt is unwound from the drum 15, after the cement has fully set, the tapes T are recovered and rewound on spools S and may be used over and over. The tapes T may 10 be of fabric or paper or of any other suitable material by which the edges of the belt will be appreciably separated as the belt is wound on the roll.

It sometimes happens that a wide belt B' 15 (Fig. 4) made to include the center or back bone portions of the hides will be thicker at the edges and thinner at the center, in which case a tape T' inserted between the belt layers at the center will be advantageous 20 in securing more complete adherence of the cemented layers to each other.

While I have described the belt as being cemented by the insertion of a strip of celluloid or pyroxylin, my improved mechanism 25 is equally applicable to belts cemented by the application of glue or other suitable cementing material.

Having thus described my invention and the advantages thereof, I do not wish to be limited to the details herein disclosed, otherwise than as set forth in the claims, but what 30 I claim is:—

1. In a belt cementing machine, means to cement strips of leather together to form a 35 double belt, means to wind said cemented belt into a tight roll, and means to insert two strips of relatively thin flexible material between successive layers in said roll of belt, said strips being inserted along the two edge 40 portions only of said belt and causing localized pressure to be applied thereto.

2. In a belt cementing machine, means to cement strips of leather together to form a double belt, means to wind said cemented 45 belt into a tight roll, and means to insert a separate strip of tape along each edge portion of said belt as it is wound on said roll, said tapes being thereby disposed between successive belt layers and causing localized 50 pressure to be applied thereto.

3. In a belt cementing machine, means to cement strips of leather together to form a double belt, means to wind said cemented belt into a tight roll, means to provide storage 55 for a plurality of tapes in said machine, and means to guide portions of separate and spaced tapes between the outer edge portions only of adjacent belt layers in said roll, thereby causing localized pressure to be applied 60 thereto.

4. In a belt cementing machine, means to

cement strips of leather together to form a double belt, and means to insert a thickness of extraneous material along each edge portion only of said belt and between adjacent layers thereof in said roll, thereby causing localized 70 pressure to be applied thereto.

5. The method of making belts which consists in cementing together strips of leather to form a double belt, pressing said cemented belt, winding said cemented belt in a tight 75 roll, and applying substantially greater pressure to the edge portions of said wound belt than to the portions inwardly removed therefrom while the cement is setting.

6. The method of making belts which consists in cementing together strips of leather to form a double belt, pressing said cemented belt, winding said cemented belt in a roll under tension, and applying substantially greater pressure to the edge portions of said 85 wound belt than to the portions inwardly removed therefrom, as said belt is wound on said roll.

7. The method of making belts which consists in cementing together strips of leather to form a double belt, pressing said cemented strips together, winding said cemented belt in a tight roll, and in substantially supporting each layer of belt in said roll by its edge 90 portions only.

8. The method of making belts which consists in cementing together strips of leather to form a double belt, pressing said cemented belt, winding said cemented belt in a roll, and in causing the pressure of said belt layers on each other in said roll to be increased between selected and transversely separated 100 longitudinally portions of said strips.

9. In a belt cementing machine, means to cement strips of leather together to form a double belt, means to wind said cemented belt, into a tight roll, and means to insert separate spaced strips of tape between selected portions of said belt as said belt is wound into a roll, said tape being thereby disposed along 105 transversely spaced longitudinal lines between successive belt layers, and causing localized pressure to be applied thereto.

10. The method of making belts which consists in cementing together strips of leather to form a multi-ply belt, pressing said cemented belt, and winding said cemented belt into a roll under tension with a definitely increased and localized pressure exerted between individual convolutions of the roll, the 110 area of localized pressure spiraling in a plane generally normal to the axis of the roll.

In testimony whereof I have hereunto affixed my signature.

WINFRED S. GRIFFITH.

CERTIFICATE OF CORRECTION.

Patent No. 1,917,296.

July 11, 1933.

WINFRED S. GRIFFITH.

It is hereby certified that error appears in the printed specification of the above numbered patent requiring correction as follows: Page 2, line 99, claim 8, after "roll" insert the words "under tension"; and that the said Letters Patent should be read with this correction therein that the same may conform to the record of the case in the Patent Office.

Signed and sealed this 22nd day of August, A. D. 1933.
